UNITED STATES PATENT OFFICE.

FRIEDRICH MÜLLER, OF VIENNA, AUSTRIA.

STARTING DEVICE FOR INTERNAL-COMBUSTION ENGINES.

Application filed August 9, 1921. Serial No. 491,005.

To all whom it may concern:

Be it known that I, FRIEDRICH MÜLLER, a citizen of the Republic of Switzerland, residing at IV Prinz Eugenstrasse 80, Vienna, Austria, have invented a Starting Device for Internal-Combustion Engines (for which I have filed applications in Austria, Nov. 23, 1916, and patent granted No. 80,682; Germany, June 12, 1920, and patent granted No. 342,853; France, May 29, 1921, and patent granted No. 535,755; Hungary, June 17, 1920; Poland, June 26, 1920; Czechoslovakia, July 28, 1920; Belgium, March 24, 1921; Switzerland, March 24, 1921; Italy, March 29, 1921), of which the following is a specification.

The invention relates to spring starters of a known type for internal combustion engines or the like, in which the starting is effected by the unstressing of a spring that is adapted to be stressed preferably by hand. The arrangement according to the invention differs from the well-known spring starters by the winding up of the springs, one or a plurality of which are provided, being effected by means of a self-locking worm gear, the parts of which are adapted to be disengaged from one another or to be disengaged as a whole from the part to be operated. By employing a self-locking worm gear, the parts of which are adapted to be disengaged from one another or to be disengaged as a whole, owing to the large gearing ratio which can easily be adopted, the operation of the arrangement is made easier and it becomes possible considerably to simplify the arrangement and manipulation, while the action is very certain.

The accompanying drawing illustrates the invention by two constructional forms.

In Figure 1, 1 is the engine, 2 the foundation or fixing frame of the engine and 3 a starting spring, which acts axially. The stressing of this spring is effected by means of a free-wheel arrangement 4, which is adapted to be coupled to the engine shaft and can be turned with a crank 5 by a self-locking worm gear, the gearing ratio of the worm gear being so chosen, that only a small expenditure of power is required to operate it with the crank. In the constructional example shown in the drawing the free-wheel arrangement takes the form of a rope drum, which is mounted on the engine shaft, is operatively connected therewith by a one-

way clutch and is adapted to be turned with the crank 5 through a self-locking worm gear wheel 6. The spring is in operative connection with the drum by means of a rope 8, which passes over the guide pulley 7, and is stressed by the rope in the axial direction. When starting, the rope drum must first be axially displaced and coupled by the clutch 9 and the pin 10 with the engine shaft. The worm gear is then released by removing the worm from the worm wheel, the spring 3 unwinding, whereby the engine is put in operation by the force of the said spring.

In the arrangement according to Fig. 2 a battery of four starting springs 3, 3', 3'' and 3''' is provided, which have to store the energy required for starting and are preferably mounted on the longitudinal side of the engine, which is opposite the control platform. These springs are made in the form of buffer springs. The transmission of the spring energy on winding up and on starting is in this case effected through toothed wheels 11 and 12 and a threaded spindle 13. The toothed wheel 11 can be turned by the crank 5 through a worm gearing 6. When the toothed wheel 12 is operated by the toothed wheel 11, the spindle 13 is axially displaced, while it is prevented from rotating by keys 14 and 15, and stresses the battery of springs. On starting, a clutch 9 is brought into operative connection with the engine shaft by a pin 10, by the toothed wheel 11 being displaced axially by disengaging means 16. The battery of springs acts through the threaded spindle 13 on the toothed wheels 12 and 11, which, on the worm gearing being disengaged, are caused to rotate and to start the machine.

The spindle 13 is prevented from rotating by the keys 14 and 15 that are located partly in a groove in the spindle, and partly in grooves in the bearings in frame 2. The threads of the spindle are square as shown and slide fully in said bearings, which are smoothed internally and without interior threads. The hub of the wheel 12 is threaded and is held against longitudinal movement by the bearings for the screw, and as the wheel is rotated the spindle is shifted longitudinally.

The remaining figures show the manner in which the locking of the worm gearing is released on starting.

In Figure 3 the worm 6, along with the spindle 17 and the crank 5, drops, at the same time turning about the point 18. The worm wheel 6' is then caused to turn through 6 the action of the starting springs.

Figure 4 shows how the worm 6 may be displaced by the eccentrics 19. The eccentrics are connected together by an arm 20 and are displaced by a hand-operated lever 10 21. On this lever being thrown over, the worm shaft 6'' is moved downwards and the worm wheel 6' is caused to disengage from the worm 6.

Figure 5 shows an arrangement, in which 15 the worm can be displaced axially. The worm 6 is slid away from the teeth of the worm wheel 6'. When the worm is out of engagement, the starting spring is released and starts the engine.

20 In the arrangement shown in Fig. 6 the worm 6 remains permanently in mesh with the worm wheel 6. The worm wheel is in operative connection with the rope drum 4 through the shaft 22. The rope drum is 25 keyed on this shaft, while the worm wheel is loosely mounted on it. For stressing the springs by means of the clutch coupling 23, the worm wheel is coupled with the shaft. The coupling is thrown in by means of the 30 hand lever 25. When this coupling is thrown out, on the engine being started, the worm gearing is disengaged from the rope drum and the shaft 22 runs loosely in the bore of the worm wheel, on the 35 starting springs coming into action.

The disengaging, on starting up, is preferably worked from the control platform, in the case of vehicles from the driver's seat.

40 Patent claims:

1. The combination with an internal-combustion engine, of a starting device therefor, comprising resilient means operable, when stressed, to rotate the engine-shaft, a self-locking worm-gearing comprising a worm and a worm-wheel adapted to be engaged with and disengaged from each other, means for disengaging said gearing from the resilient means and operative connections between said worm-gearing and said resilient means.

2. The combination with an internal-combustion engine, of a starting device therefor, comprising resilient means operable, when stressed, to rotate the engine-shaft, a worm-gearing comprising a worm and a worm-wheel, means for disengaging said gearing from the resilient means, a shaft rotatable with and carrying said worm-wheel, a drum carried by and rotatable with said shaft, and a flexible connection between said drum and said resilient means for stressing the latter when said drum is rotated in one direction.

3. In starting devices for engines, the

combination of a spring, a longitudinally moving member adapted to put the spring under compression, a crank arm having intermediate gearing to actuate the longitudinally moving member to compress the 70 spring, a power shaft, and a clutch to connect the spring with the power shaft to rotate it.

4. In starting devices for engines, the combination of a spring, a plunger adapted 75 to compress the spring, a crank arm, a shaft, a drum on the shaft, a cord on the drum and connected with the plunger, a worm gear wheel on the shaft, a worm on the crank arm shaft, and a clutch adapted to connect 80 the drum with the power shaft of the engine.

5. The combination with an internal-combustion engine, of a starting device therefor, comprising resilient means operable, 85 when stressed, to rotate the engine-shaft, a worm-gearing comprising a worm and a worm-wheel, means for rendering the worm-gearing inoperative to hold the resilient means, a shaft rotatable with and carrying 90 said worm-wheel, a drum carried by and rotatable with said shaft and shiftable into and out of clutching engagement with the engine-shaft, and a flexible connection 95 between said drum and said resilient means for stressing the latter when said drum is rotated in one direction.

6. The combination with an internal-combustion engine, of a starting device therefor, comprising resilient means operable, 100 when stressed, to rotate the engine-shaft, a worm-gearing comprising a worm and a worm-wheel adapted to be engaged with and disengaged from each other, a shaft 105 rotatable with and carrying said worm-wheel, a drum carried by and rotatable with said shaft and shiftable into and out of clutching engagement with the engine-shaft, and a flexible connection between said drum and said resilient means for stressing the latter when said drum is rotated in one 110 direction.

7. The combination with an internal-combustion engine of a starting device therefor 115 comprising a spring device operable, when stressed, to rotate the engine shaft, a self-locking worm-gearing, a free wheel arrangement on the starting shaft for stressing the spring device by means of the self-locking 120 worm-gearing, a clutch between the free wheel arrangement and the engine shaft, and means for throwing in the clutch and for releasing the locking of the worm gearing on starting.

8. The combination with an internal-combustion engine of a starting device therefor comprising a spring device, a self-locking worm gearing comprising a worm and worm wheel for stressing said spring device and 125 hold the spring in tension, and means for 130

releasing the spring device by disconnecting two of these parts.

9. The combination with an internal combustion engine of a starting device therefor comprising a spring device, a self-locking worm gearing for stressing said spring device and maintaining the spring in tension, said worm gearing comprising a worm and worm wheel which are adapted to be disengaged from each other for releasing the 10 spring device.

Vienna, Austria, July 18, 1921.

FRIEDRICH MÜLLER.
